UNITED STATES PATENT OFFICE.

EDWARD G. WHITACRE, OF WELLSVILLE, OHIO.

HEATER.

Application filed July 28, 1922. Serial No. 578,163.

To all whom it may concern:

Be it known that I, EDWARD G. WHITACRE, a citizen of the United States, and a resident of Wellsville, in the county of Columbiana and State of Ohio, have invented a new and Improved Heater, of which the following is a full, clear, and exact description.

This invention relates to improvements in heaters, and more particularly to domestic heaters for hot water, steam or vapor use, but primarily for heating water, an object of the invention being to provide a heater of the character stated which can be easily and conveniently taken apart and thoroughly cleaned and assembled without danger of leakage after assemblage.

A further object is to provide a heater of the character stated composed of inner tubes, surrounded by larger concentric tubes forming an annular water space, and radial tubes fixed to the inner concentric tube and arranged in spiral form with improved arrangement of burner, whereby the heat is obstructed by the radial tubes at a multiplicity of points to insure a rapid heating of the water.

A further object is to provide a heater of the character stated with an improved construction and arrangement of burner whereby all of the heat units are utilized and a maximum of efficiency had.

With these and other objects in view, the invention consists in certain novel features of construction and combinations, and arrangement of parts, as will be more fully hereinafter described and pointed out in the claim.

In the accompanying drawings—

Figure 1 is a view in vertical longitudinal section illustrating my improved boiler.

Figure 2 is a top plan view.

Figure 3 is a fragmentary view in vertical section of the upper portion of the heater taken at right angles to Figure 1.

Figure 4 is a view similar to Figure 3 of the lower portion of the heater.

The Figures 3 and 4 are taken in section on the line indicated by the arrows in the Figures 2 and 5.

Figure 5 is a view in horizontal section on the line 5—5, of Figure 1.

Figure 6 is a fragmentary view in section illustrating a modification.

1 represents the base and 2 the head of my improved heater. The base 1 and the head 2 are made with circular concentric grooves 3

in which gaskets 4 are located, and concentric inner and outer tubes 5 and 6 respectively are located in the grooves 3 of the head 2 and base 1 and rest upon the gaskets 4 and are secured in such position by clamping rods 7.

The rods 7 are located in the water space 14 between the tubes 5 and 6, and are screwed into threaded sockets 8 in the head 2. The lower ends of the rods 7 project through openings 9 in base 1 and have nuts 10 screwed onto their lower ends. Cupped washers 11 with packing rings 12 therein are interposed between the nuts 10 and the surface of base 1 so that when the nuts 10 are screwed home there is no possibility of leakage.

The base 1 is formed with an inlet water passage 15 communicating with the water space 14 and having a coupling nipple 16 projecting thereto for the attachment of a water supply pipe not shown.

The head 2 is formed with a water outlet passage 17 with which a nipple 18 communicates for attachment to a water outlet pipe not shown.

The head 2 has a central heat outlet 19 which is preferably inclined or flared so as to give the maximum of draft, and the base 1 is in the form of a ring so that its open center communicates with the interior of tube 5. As this base 1 may rest directly on a support, openings 20 are provided in the wall thereof for the free circulation of air to aid combustion.

The tube 5 is provided with a series of radial water tubes 21. These water tubes are fixed in openings in the tube 5 in any approved manner, but preferably by welding so as to insure tight joints. The tubes 21 are in a spiral series, forming a spiral path through the tube 5 for the heat or products of combustion which are supplied by my improved burner 22. This burner 22 is mounted centrally in the base 1 and has an annular gas space 23 with a ring cap 24 thereon secured preferably by screws 25 and having burner orifices 26 in its opposite faces so that the flame is directed in small jets both inwardly and outwardly and upwardly. The outwardly discharging jets are directed against the inner face of the tube 5 while the inner jets impinge against the tubes 21 and the heat from both series of jets is directed in a spiral path through the tube 5 to insure the heating of all the sur-

faces and a rapid heating of the water in the water space 14 and tubes 21.

The burner 23 may be secured in the base in various ways.

- 5 I have illustrated a simple form of construction in which a pipe 27 projects through an opening 28 in the wall of the base and is screwed into the burner 23 at its inner end, and at its outer end has an enlarged Bunsen coupling member 29 screwed thereon. A sleeve 30 may be located on pipe 27 against the inner face of the base 1 so that the parts are rigidly coupled.
- 10

It is, of course to be understood that the 15 particular manner of securing the burner in the base may be varied, but in any case, the burner would be removable and readily taken apart so that it can be effectually cleaned as occasion may require.

20 The Bunsen coupling 29 will supply air to the gas to form the desired mixture, and the auxiliary air, or additional air, will be supplied through the base to give a free burning and insure the maximum utilization of heat units.

25 In operation, water entering the passage 15 will flow into the water space 14 between the tubes 5 and 6 and as it passes upwardly it will flow back and forth through the tubes 30 21 and then out through the outlet passage

17. During this passage of the water, the 35 heat will be directed against the inner face of tube 5 and against the outer faces of tubes 21 as the flame and gases are carried in spiral path through the tube 5 and out the outlet 19. This will insure a rapid and efficient heating of the water at a minimum expenditure of fuel, and while I have referred to gas as the fuel, it is obvious that the invention 40 is not limited to gas, as I may employ any desired fuel either liquid, gas, or vapor. It is, of course, to be understood that my invention is not limited to any particular use, as it is adapted for many uses either for 45 heating water for domestic purposes, or for use in connection with radiators for heating purposes.

In Figure 6 I illustrate a modification

showing a single gasket X on which both tubes 5 and 6 may be supported, instead of 50 the double gasket construction illustrated in the other forms, and it is to be understood that this single gasket construction is adaptable for both heads.

I would also have it understood that 55 while I have illustrated a particular form of burner for the water heater, I would have it understood that the invention is not limited thereto as it is obvious that steam or other fluid might be employed for heating 60 the water.

It will be noted that my improved heater can be readily taken apart, cleaned and reassembled, without requiring skilled labor, and that its original cost will be reasonable 65 and the results attained highly satisfactory.

The heater may, of course, be constructed of any suitable material as for example, brass, copper or steel, and may be made in any sizes to suit the trade.

70 Various slight changes might be made in the general form and arrangement of parts described without departing from my invention, and hence I do not limit myself to the precise details set forth, but consider 75 myself at liberty to make such changes and alterations as fairly fall within the spirit and scope of the appended claim.

I claim:

A water heater, comprising a ring-shaped 80 base having a water passage therethrough, said passage opening out through the top of the ring, said ring having also a lateral opening opposite the water passage, a head having a central outlet for the products of combustion and a water outlet at one side of the first named outlet, two concentric shells spaced to provide between them a water chamber, means for detachably securing the shells to the base and head, water 85 tubes in the inner shell communicating with said water chamber, a burner, and a fuel pipe in the lateral opening of the base and supporting the burner within the ring.

EDWARD G. WHITACRE.
